UNITED STATES PATENT OFFICE.

CHARLES F. L. KAUFMANN AND WALLER L. KAUFMANN, OF SANTA ANA, CALIFORNIA.

BUMPER.

Application filed July 11, 1925. Serial No. 42,997.

To all whom it may concern:

Be it known that we, CHARLES F. L. KAUFMANN and WALLER L. KAUFMANN, citizens of the United States, residing at Santa Ana, in the county of Orange and State of California, have invented a new and useful Bumper, of which the following is a specification.

This invention relates to bumpers and more particularly to an improved modification of the bumper disclosed in our copending application Serial Number 5,999 filed January 31, 1925.

An object of this invention is to provide an improved form of construction of the intermediate impact section of the bumper that is between the frame members of the vehicle to which the same is attached so as to provide a rigid impact section, which rigid impact section is yieldably mounted in position in advance of the frame of the motor vehicle.

Other objects and advantages of this invention will be apparent from the following detailed description of a preferred embodiment thereof as illustrated in the accompanying drawings.

In the drawings:

Fig. 1 is a front elevation of a bumper embodying this invention.

Fig. 2 is a top plan view thereof.

Fig. 3 is a sectional end elevation taken substantially on the line 3—3 of Fig. 1.

Fig. 4 is a sectional end elevation taken substantially on the line 4—4, of Fig. 2.

Fig. 5 is a detached plan view of a rigid impact section and yieldably supporting ends thereof.

In the preferred form of our invention, 1 illustrates a forward impact section composed of a plurality of spring steel bars 2 and 3, which spring steel bars are looped at their ends to provide eyes 4 through which bolts 5 extend and which bolt 5 is provided 45 between the bars 2 and 3 with spacers 6 so as to hold the bars rigidly spaced apart at their ends. A rear supporting bar 7, mounted in clamps 8, is connected by means of clamps 9 to intermediate bars 10. The intermediate bars 10 are looped as illustrated at 11 and are twisted at right angles as illustrated at 12 to provide horizontally extending portions 13 which extend through and are rigidly clamped in position by means 55 of clamps 14, which clamps 14 likewise sup-

port the bars 2 and 3 and maintain the same spaced apart.

The clamps 8 which support the bumper from the frame of the vehicle preferably comprise a casting 15 curved as illustrated 60 at 16 to proximate the curvature of the horn of the vehicle frame and which are provided at their forward end with flanges 17 through which bolts 18 are extended. The bolts 18 likewise pass through a casting 19 and provide a clamp therewith. The bars 7 and 10 are clamped together and held in position between the flange 17 of the casting 16 and the casting 19 by means of the bolts 18. The portion of the casting 70 15 which is curved to proximate the curvature of the horn of the motor vehicle is preferably secured thereto by means of bolts 20. The clamps 14, by means of which the intermediate bars 10 are clamped to the 75 forward impact section 1, preferably comprise a hollow casting 21 which has a slot 22 extending horizontally therethrough and recesses 23 of approximately the width of the bars 2 and 3 of the forward impact section 80 so that the bars 2 and 3 fit closely within the slots 22 and recesses 23. The recesses 23 at their intermediate ends provide faces 23^a against which the adjacent edges of the bars 2 and 3 abut.

A second casting 24 is provided which likewise provides a nameplate or symbol casting for the bumper. This casting 24 is secured to the casting 20 by means of bolts 25 at its ends and by means of a stud bolt 85 26 at its center, the stud bolt 26 being screw threaded into the portion 27 of the casting to the rear of the horizontal portions 13 of the intermediate bars 10. In addition to the looped portions 11 of the intermediate bars 90 10, means are provided for absorbing the impact force imparted to the impact section 1, which means preferably comprise cup sections 28 of the casting 19 which are tapered as illustrated at 29 to receive the tapered 95 ends of the resilient impact members 30 which impact members 30 are preferably constructed of rubber or like material. The casting 14 likewise provides a recess 31 into which the forward end 32 of the resilient 100 impact member 30 fits. The clamps 9 which clamp the inner ends of the intermediate bars 10 to the supporting bar may be of any desired form, but are herein illustrated as comprising clips secured together at their 110

- lower ends by means of bolts 33. The impact member 30 is constructed of rubber or like resilient material and is so mounted between the looped ends of the bars 10 as to provide a resilient yielding member which acts together with the spring loop 11 formed in the bar 10 to absorb the impact shock which may be imparted to the impact section 1 of the bumper.
- 10 By this construction of clamp 14, the forward edge 36 of the horizontal portions 13 of the intermediate bars 10 may be projected forward to a position in the same vertical plane with the front face 37 of the bars 2 and 3 and casting 24 may be employed to rigidly and positively maintain all of the bars 2, 3, 10 in position. This construction also enables the use of a central bolt, such as 26, to prevent the castings 24 and 14 from being distended from their position, and permits the bars to be retained in position and to prevent rattling after the same have received a violent impact.
- 15 The bolt 26 is threaded at both ends and the intermediate section thereof provides a spacer for the bars 13. Fitted over the forward end of the bolt 26 is a washer 38 which has a pair of ears 39 which act as spacers for the bars 13. Screw threaded to the bolt 20 26 is a nut 40 to maintain the washer 38 in position. Nuts 41 are screw threaded to the forward ends of the bolts 26 to maintain the castings 24 in position.

Fig. 5 illustrates a modified form of mounting for mounting the intermediate bar 10 to the rearward supporting bar 7 in which modification a spacer 34' is mounted between the ends of the bars 7' and 10' and a bolt 35' is passed through bores formed in the respective sections of the bars 7' and 10' and through the spacers 34' to secure the same together.

This modification may be particularly desirable for use in connection with many of the common forms of clamps or brackets for securing the bumper to the motor vehicle frame.

Having fully described a preferred embodiment of this invention, it is to be understood that we do not wish to be limited to the exact construction herein set forth, which may be, obviously, varied in detail without departing from the spirit of the invention as set forth in the appended claims.

We claim:

1. In a bumper, a forward impact section connected at spaced points to a pair of flat steel bars having their flat faces in horizontal planes, whereby the impact section is provided with a rigid central portion, and means for attaching such bumper to a motor vehicle.
2. In a motor vehicle bumper, a pair of vertically spaced spring steel buffer bars connected at spaced points to a pair of flat

steel bars having their flat faces in horizontal planes, whereby the vertically spaced bars are provided with a rigid central portion, and means for attaching such bumper to the vehicle.

3. In a motor vehicle bumper a forward impact structure, a secondary and supporting structure connected by spring loops to the front structure, and impact members disposed between said structures so that the forces of the impact may be gently absorbed by said impact members and said spring loops, and a rigid impact section so connected to the forward impact structure that its forward edges are aligned with the front sides of the members forming the forward impact structure.

4. A motor vehicle bumper, comprising a plurality of vertically spaced bars, a pair of flat steel bars having their flat faces disposed in horizontal planes joined to the medial portion of the said spaced bars so as to cause the same to be rigid horizontally.

5. A motor vehicle bumper, comprising a plurality of vertically spaced bars, a plurality of flat steel bars having their flat faces disposed in horizontal planes, the latter said bars being joined to the medial portion of the first said bars so as to cause the same to be rigid horizontally, and impact members supported in position to absorb impact imparted to the rigidly joined portion of the said bars.

6. A motor vehicle bumper comprising an impact bar adapted to extend transversely of the vehicle, spaced clamps secured to medial points of said bar, a pair of flat steel bars having their greatest transverse dimension in horizontal planes and held by said clamps in position to reinforce the impact bar, and a secondary bar carrying such impact bar.

7. A motor vehicle bumper, comprising a pair of attaching members holding the bumper directly in front thereof, impact bars having rigid sections formed of a pair of bars having their greatest transverse dimension in horizontal planes, and means mounting such bars in position and bearing against said attaching members to absorb impact shocks.

8. A bumper comprising a forward impact section, a pair of intermediate bars looped at their ends and twisted intermediate their ends so as to provide horizontally extending sections at the front of the bumper for reinforcing the said impact section and making the center thereof rigid, a supporting bar secured to the intermediate loop bars, means for clamping the supporting bar and loop bars in position, means for securing the said loop bars to the impact section, and impact members interposed between the said securing means.

9. A bumper, comprising a pair of verti-

5 cally spaced spring steel bars, a plurality of flat steel bars positioned intermediate the said vertically spaced bars and rigidly connected to the vertically spaced bars, means for securing the bumper in position, and resilient impact members interposed between the said securing means and the said impact section.

10. In a bumper, the combination of a 10 plurality of vertically spaced bars having their front faces in the same vertical plane, intermediate bars disposed between the said vertically spaced bars and presenting their edge faces in the plane of the said front 15 faces of the vertically spaced bars, and means for securing the said vertically spaced bars and the horizontally disposed bar in position.

11. In a bumper, the combination of a 20 plurality of vertically spaced bars having their front faces in the same vertical plane, a plurality of horizontally disposed and spaced bars mounted intermediate the first said vertically spaced bars and presenting 25 edge faces in the same vertical plane with the front faces of the first said vertically spaced bars, and means for rigidly securing the said bars together.

12. In a bumper, the combination of a 30 vertical impact section, a pair of intermediate bars looped at their opposed ends and twisted at right angles so as to present horizontally disposed sections for reinforcing the said impact section, means for rigidly 35 securing the said intermediate bars to the impact section, and means for securing the said intermediate bars to a motor vehicle frame.

13. In a bumper, the combination of a 40 forward impact section, a pair of intermediate bars looped at their opposed ends and twisted at right angles at their adjacent ends, and means for securing the said intermediate bars together and to the said impact 45 section at the twisted sections.

14. In a bumper, the combination of a 50 forward vertically extending impact section, a pair of intermediate bars looped at their opposed ends and twisted at their adjacent ends, means for securing the said intermediate bars to the said vertical impact section, the said vertical impact section being looped rearwardly at its opposite ends.

15. In a bumper, the combination of a plurality of vertically spaced bars, a plurality of intermediate bars looped at their opposed ends and twisted at right angles at their adjacent ends, means for securing the said intermediate bars together and to the vertically spaced bars and so as to maintain the vertically spaced bars in spaced relation, the said vertically spaced bars being curved at their ends and being provided at their ends with spacers for maintaining the vertically disposed bars in spaced relation at 65 their ends.

16. In a motor vehicle bumper, a forward impact structure, a plurality of flat steel bars having their flat faces in horizontal planes connected by spring loops to the 70 front structure, means for attaching the bumper to the motor vehicle, impact members disposed between the said securing means and the said flat steel bars so that the forces of impact may be gently absorbed 75 by said impact members and said spring loops, the flat steel bars being so connected to the forward impact structure that their forward edges are aligned with the front side faces of the members forming the forward impact structure.

17. In a bumper, the combination of a forward vertically extending impact section, a pair of intermediate flat steel bars looped at their opposite ends and twisted at their adjacent ends so as to provide forward sections having their flat faces disposed in horizontal planes, means for securing the said intermediate bars to the said vertical impact section, the said flat steel bars being looped rearwardly at their opposite 85 ends.

18. In a bumper, the combination of a forward impact section, a pair of intermediate flat steel bars looped at their opposite 90 ends and twisted at right angles at their adjacent ends so as to provide a rigid forward section having their flat faces disposed in horizontal planes, and means for securing the said intermediate bars together 100 and to the impact section at the twisted sections.

Signed at Los Angeles California, this 30th day of June 1925.

CHARLES F. L. KAUFMANN.
